CLAIM

The ornamental design for terminal cover for an electromagnetic contactor, as shown and described.

DESCRIPTION

FIG. 1 is a top isometric view of a terminal cover for an electromagnetic contactor;
FIG. 2 is a bottom isometric view of a terminal cover for an electromagnetic contactor;
FIG. 3 is a right side perspective view of a terminal cover for an electromagnetic contactor;
FIG. 4 is a front perspective view of a terminal cover for an electromagnetic contactor;
FIG. 5 is a rear perspective view of a terminal cover for an electromagnetic contactor;
FIG. 6 is a top perspective view of a terminal cover for an electromagnetic contactor; and,
FIG. 7 is a bottom perspective view of a terminal cover for an electromagnetic contactor.
